UNITED STATES PATENT OFFICE.

CUTHBERT BURNETT, OF HARTLEPOOL, COUNTY OF DURHAM, ENGLAND.

MINING WEDGE OR TOOL FOR BREAKING UP COAL, &c.

SPECIFICATION forming part of Letters Patent No. 351,850, dated November 2, 1886.

Application filed March 9, 1886. Serial No. 194,625. (No model.)

To all whom it may concern:

Be it known that I, CUTHBERT BURNETT, a subject of the Queen of Great Britain, residing at Hartlepool, in the county of Durham, 5 England, have invented certain new and useful Improvements in Mining Wedges or Tools for Breaking up Coal or other Mineral, of which the following is a specification.

This invention consists of a mining-wedge 10 for breaking up coal and other minerals in which a wedge-shaped jambing-bar inclosed between parallel bars or feathers, or a parallel jambing-bar inclosed between taper bars, or a taper jambing-bar inclosed between taper bars, 15 is combined with anti-friction rollers or balls so arranged and operating by the rollers ascending on the inclined surfaces as to produce expansion of the bore-hole and bursting the walls of same, suitable means being provided 20 for actuating the jambing-bar relatively to the feathers and rollers, all as hereinafter described.

In the accompanying drawings I have shown at Figure 1, in vertical longitudinal section, a 25 mining wedging-tool with the key or handle for actuating the ratchet of the threaded nut, and at Fig. 2 a cross-section on line $x-y$ of Fig. 1; and Fig. 3, a cross-section on line $x'-y'$ of the same figure. Fig. 4 is a vertical trans- 30 verse section showing position of bore-hole in mass of coal into which the instrument is introduced. This figure is drawn to a reduced scale to the previous figures. Fig. 5 shows in vertical longitudinal section, on a larger scale 35 than Fig. 1, the outer or front end of the wedging apparatus, showing the compound ratchet-brace. Figs. 6 and 7 are an end view and vertical cross-section, respectively, of the same. Fig. 8 is a sectional side elevation of a 40 modified arrangement of the outer or front end of the wedging apparatus, and Fig. 9 a plan of same. Figs. 10 and 11 are respectively part sectional side view and plan of the ratchet lever or handle detached.

45 The same letters refer to like parts in all the figures.

Referring specially to Figs. 1 to 7, A is the wedge, formed or provided at or in continuation of the end of the screw, and made thinner 50 at its screw end and thicker at its other end, where it is formed with an enlargement or

head, A^x . This screw and wedge-bar, conveniently made with a plain or parallel part, A' , between the wedge A and the screw A^2 , is inclosed between two bars or feathers, B and B^x , which are placed in the bore-hole. For 55 this purpose I makethem of a channel-section, as shown in Fig. 2—that is to say, with a ledge or rib on each side, which inclose the wedge-bar, and thus, while affording greatly increased strength, serve also to keep the rollers C in place sidewise, thus enabling me to dispense with a frame in which the rollers are mounted.

Instead of the feathers being riveted into the 60 flange or shoulder D, resting against the face of the coal, I prefer either to dovetail the feathers into the shoulder or flange D or provide them, as herein shown, with T-heads fitting into corresponding recesses in the flange D. 65 These bars are from near the end formed with a long easy taper inside, and the bottom bar, B^x , which has to bear the greater weight or strain, is made stronger than the top bar, B, as shown, and the rollers C or balls are placed in 70 the intervals between the inner taper bar, A, and the two outer taper bars, B and B^x .

There are shoulders at $b-b$ and at A^x and A^o for keeping the rollers in. A nut, E, placed 75 on the screw and abutting against the ends of the two outer bars, gives facility for pulling the inner wedge-bar, A, out toward the face of the coal, whereby the rollers C, while ascending on the inclines of the inner taper bar, A, and the inclines of the outer taper bars, 80 B and B^x , will force the two latter apart, thus bursting the bore-hole. The nut E is formed with a flange, which is held in place against the flange D by means of a bearing-plate, E^x , and two (or more) bolts, D^2 , the shoulder D and 85 plates E^x having lugs therefor, as shown. To turn the nut E, I employ the following appliance:

On the nut I provide a square, E^2 , for a ratchet handle or lever to fit on. The ratchet-lever may suitably be about two feet in length, and preferably constructed as shown in Figs. 10 and 11, which can conveniently be operated in a limited space. In this manner the wedge is worked in the first instance as far as possible; but when the work becomes too hard to be conveniently done I use a supplementary 90

purchase and lever. For this purpose I take the ratchet-lever off the square E^2 and first lock the "nut" or ratchet-wheel K^2 , Figs. 10 and 11, by means of the pawl K^5 , and now use 5 the ratchet-lever as an ordinary lever and apply it to the square H^4 of the lever H ; or I may use an ordinary lever fitting the square H^4 as a supplementary lever.

The nut E is provided with a pawl-wheel, E' , the pawl F for which is fitted in a fork, G , swiveling on the plain parts of the nut E like a ratchet-brace, and the fork G is provided with a cam-like slot, G' , for a bush or boss, forming a lever, H , to work in, which boss is 15 fitted with the square H^4 for the ratchet-lever K , (or supplementary lever.) This boss or lever H is mounted freely on a pin, D' , fixed to an arm or bracket, D^* , extending from the flange D , which is secured to the ends of the 20 two aforesaid lateral bars $B B^*$, and has a segmental edge incision, which fits the circumference of a smaller roller, H^3 , also mounted freely on a pin which is fixed in the fork end $H' H^2$ of the lever H . This roller H^3 works 25 in the cam-slot in the fork G . As the ratchet or supplementary lever is worked the boss of the lever H will, with the edge of its segmental excision, mount on the other or smaller roller, H^3 , and thus move the latter in and with the 30 fork G , in which it is placed, and therewith also the pawl F , connected thereto, thus turning the pawl-wheel E' . In the return-stroke of the lever on the square H^4 the boss H will resume its first position in the slot in the fork 35 G . By this construction of parts I obtain an increased power in direct proportion to the ratio of leverage between the lever H and lever G , the ratio of leverage being nearly uniform, while the whole is self-contained.

40 By the improved form of the feathers $B B^*$, and thus also doing away with a frame or carriage in which the rollers are to be mounted, the apparatus is much reduced in size, so that the hole into which it is inserted is drilled 45 much smaller. The friction is also much reduced, while the general efficiency and convenience of the apparatus is enhanced. The wedge-bar, it will be seen, travels double the distance of the rollers. I thus obtain twice 50 the power of any other wedge of the same taper and length of taper and pitch of screw. The wedge might be made double; but such increase of power I do not at present want. It will also be understood that the improvements 55 hereinbefore described are also applicable to a wedge-shaped jambing-bar with parallel feathers, or to a parallel jambing-bar with taper feathers.

60 Referring again to the ratchet-lever shown in Figs. 10 and 11, K is the handle of same, the head of which is formed with a fork carrying between its two prongs $K' K'$ the ratchet-wheel K^2 , the projecting cylindrical bosses K^3 of which revolve in bearings formed 65 by the said prongs $K' K'$.

Pivoted to the base of the fork, on one side, there is a pawl, K^4 , for rotating the ratchet-

wheel K^2 , and kept to its work by a spring, and on the other side is pivoted a hooked catch, K^5 , by which the ratchet-wheel K^2 may be locked with the handle when desired, as already explained. By this construction of ratchet-lever I may, when applied to the square end of the crank H , obtain such an advantageous relative position for the handle K as 75 may be found most convenient for the effective operation of same without shifting the handle from either of the square ends, whichever it might at the time be applied to; also, by locking the ratchet-wheel with the handle by means 80 of catch-pawl K^5 , (it being observed that the base of the teeth of the ratchet is somewhat square-cut,) I am enabled to use this handle as an ordinary plain handle, and for operating on either of the square ends, left or right. 85

The modified wedge apparatus shown in Figs. 8 and 9 differs from that shown in Figs. 1, 2, 3, 5, 6, and 7 in that conical rollers L are interposed between the flange or shoulder D and the flange end of the nut E for the purpose of materially diminishing the friction at this place. Fig. 9 also shows more clearly the holes for the T -heads of the feathers or bars $B B^*$.

The application and action of my improved 95 mining wedging-tool in, say, for instance, the ordinary coal-mining operations is as follows: The coal having been cut away at its lower part and the wedge hole or holes drilled, as shown by Fig. 4, the wedging appliance is inserted into such a hole as shown at Fig. 1. The ratchet handle or key K is then affixed onto the square E^2 , formed on the extended portion of the nut E , which latter is thereby rotated, and the said nut E , bearing against the shoulder D , will begin to withdraw the wedge A . The operator will continue this, I may say, direct action of the handle K on the square end E^2 of the nut E until more power is required than can be thus directly obtained. He then 100 shifts the handle or key onto the square H^4 of the forked crank H , and by imparting successive to-and-fro partial rotations to same the roller H^3 , acting against the cam-slot G' of the fork G , will cause the pawl F on the fork 105 G to pass, say, a tooth at each oscillation caused by the motion given to the crank H , and thus very great power will be obtained, and thereby causing the final bursting of the bore-hole, with, of course, a proportionate loss 110 of speed in the motion. The wedge-bar A is prevented from being withdrawn too far, and so allowing the rollers to pass its larger end, by said end A^* being swelled out or enlarged, and the ends b of the outer bars, $B B^*$, being 115 also enlarged or bent inward, as already stated, this latter formation of the bars $B B^*$ further preventing the rollers escaping, as already explained, when the bar A is in the position shown at Fig. 1. 120

I claim—

1. The inner jambing-bar having one long tapering portion, A , and shoulders $A^* A^*$ at the respective ends of the taper, in combina-

tion with the long tapering bars or feathers B B^x, with shoulders b and flange abutting against the face of the coal, and ranges of numerous anti-friction rollers in the spaces between the bars A and B B^x, and confined by the shoulders A^x, A^o, and b, and means, substantially as specified, for moving the jambing-bar endwise and forcing the inclosing-bars apart, and, vice versa, allowing them to come together, substantially as set forth, whereby the required power is obtained and the splitting action concentrated and gradual, substantially as set forth.

2. The combination of an inner jambing-bar, A A' A², having shoulders A^x A^o, the inclosing channeled bars or feathers B and B^x, with shoulders b, and the anti-friction rollers C, arranged in the intermediate tapering spaces, confined by the shoulders A^x, A^o, and b, the said feathers B B^x being united to a flange, D, which rests against the face of the coal, and the screw A² of the jambing-bar having a nut, E, with pawl-wheel E', and square E², for ratchet handle or lever, and provided with supplementary or slower purchase device, with square for ratchet handle or lever, substantially as set forth.

3. The combination, with an inner jambing-bar with screwed end and inclosing bars or feathers, with abutting shoulder or flange D,

and rollers arranged in intermediate tapering spaces, of a nut, E, on said jambing-bars, with pawl-wheel E', and square E², for ratchet lever or handle, a supplementary purchase-fork, G, swiveling on said nut and provided with a pawl, and having an internal cam-surface, G', for a roller, H³, to work against, which operates in conjunction with the boss of the lever H, on which it is mounted, said lever pivoting on a fulcrum, D', on the aforesaid flange D, and being provided with a square, H⁴, for ratchet lever or handle to work such supplementary or slower purchase-gear, substantially as set forth.

4: The combination, with an inner jambing-bar with screwed end and inclosing bars or feathers, with abutting shoulder or flange D, and rollers arranged in intermediate tapering spaces, of a nut, E, on said jambing-bar, and taper rollers between the flange D and the nut E, for diminishing the friction, substantially as set forth.

In testimony whereof I affix my signature, in presence of two witnesses, this 8th day of February, 1886.

CUTHBT. BURNETT.
